UNITED STATES PATENT OFFICE

JOHN REAGAN AND ARTHUR BERNARD, OF LIVERMORE FALLS, MAINE

SUCTION-BOX HEAD FOR PAPER-MAKING MACHINES

Application filed September 24, 1929. Serial No. 394,857.

This invention relates to paper making machinery and more particularly to the heads of the suction boxes of said machinery, and has for one of its objects to provide, in a manner as hereinafter set forth, a head of the aforementioned character, having means thereon for co-action with means on a detachable handle or rod whereby an extremely strong connection is had between the handle and head.

Another important object of the invention is to provide a suction box head or deckle having a detachable handle which may be removed after the head is adjusted or set, thus permitting a single handle to be used for any number of heads.

Another object of the invention is to provide a suction box head or deckle embodying means for detachably connecting a handle thereto without the necessity of forming an opening through the head for the passage of the handle and through which the fluid may leak.

The invention aims to provide a suction box head having a socket member mounted centrally thereon, and provided with a transverse pin for the purpose of connecting a bayonet slotted handle or bar thereto, the slotted end of said bar being provided with a novel reinforcing means for strengthening the end of the bar and said sockets being provided with an outwardly diverging flange constituting guide means for directing the bar into the socket.

Other objects of the invention are to provide a device of the aforementioned character, which will be simple in construction, strong, durable, efficient in its use, and which may be manufactured at low cost.

Other objects and advantages of the invention will become apparent from a study of the following specification, taken in connection with the accompanying drawings, wherein like characters of reference designate corresponding parts throughout the several views, and wherein:

Figure 1 is a side elevation of a suction box head showing the improvement constituting this invention associated therewith.

Figure 2 is a vertical sectional view of the

socket which is mounted on the suction head.

Figure 3 is a side elevation, partly broken away in section, of the upper end of the handle rod or shaft, which is inserted in the socket.

Figure 4 is a detail in side elevation of the reinforcing means for the upper end of the rod.

Figure 5 is a top plan view of the upper end of the rod.

Referring to the drawings in detail, the reference character 1 designates a suction box head or deckle of conventional design having mounted on its peripheral edge, a gasket 2, of rubber or any other suitable material. An externally threaded neck 3 is mounted centrally on one side of the head 1 and threaded on the lower end of the neck 3 is a tubular socket forming member designated generally by the reference character 4. The socket 4 is provided with a bore 5, of uniform diameter, which merges, at its upper end, with an internally threaded counter bore 6, which connects with the lower threaded end of the neck 3. The lower end of the socket 4 is provided with an obtuse guide flange 7, into which the lower end of the bore 5 merges. Spaced annular flanges 8 are provided on the outer periphery of the socket 4, one of said flanges at the upper end thereof and the other of the flanges on the intermediate portion of the socket. A pair of oppositely disposed brackets in the form of angle irons and designated by the reference character 9 are mounted on the head 1 on opposite sides of the neck 3 and are connected to said head, through the medium of the threaded securing elements 10. The brackets 9 are provided with inturned right angularly disposed end portions 11, which slidably embrace the side walls of the socket 4, intermediate the flanges 8 thereon, and these brackets are for the purpose of permitting rotating of the socket 4 on the neck 3, but will limit the downward movement of said socket thereon and prevent the complete detachment of said socket from the neck. The socket 4 is provided with a transverse pin 12, which traverses the bore 5, adjacent the lower end thereof.

A detachable handle designated generally 100

by the reference character 13 is provided for removing the head 1 from the suction box of the paper making machine and said handle 13 comprises an elongated hollow tube 14, of uniform diameter, having a handle forming T-head 15, on one end. The opposite end of the tube 14 is open and is provided with oppositely disposed bayonet slots 16. A bifurcated reinforcing cylinder 17 is rotatably mounted in the upper end of the tube 14, and is provided, adjacent its lower end with, an annular groove 18. The slot 19 which is formed by the bifurcated end of the cylinder is adapted for alignment with the bayonet slot 16 of the tube 14, and is coextensive with the longitudinal portions of said bayonet slots. A stop pin 20 is mounted in the tubes 14 and projects inwardly therefrom and extends into the annular groove 18 for the purpose of rotatably securing the reinforcing cylinder 17 therein, and retaining said cylinder against longitudinal movement. A stop plug 21 is mounted in the tube 14, in spaced relation below the lower ends of the reinforcing cylinder 17, through the medium of a cross pin 22, and interposed between the stops 21 and lower end of the cylinder 17 is an expansible coil spring 23.

In the use of the invention, the socket 4 is mounted on the neck 3 and the brackets 9 are then mounted in place on the head 1, as clearly shown in Figure 1 of the drawings.

The slotted end of the tube 14 is then placed in the bore 5 of the socket 4 and pushed upwardly therein, the furcations on the ends thereof extending on opposite sides of the cross pin 12.

When the lower ends of the bayonet slot 16 engage the cross pin 12, a slight turn is imparted to the tube 14 for seating the cross pin 12 in the right angularly disposed lower end portion of the bayonet slot, as will be understood. It will be here pointed out that the annular groove 18 in the reinforcing cylinder 17 is of greater diameter than the retaining screw 20, and it will therefore be seen that a very slight longitudinal movement of the reinforcing cylinder in the tube may be had. By reason of this, when the cross pin 12 has been seated in the right angularly disposed pocket of the bayonet slot, the reinforcing cylinder 17 which is caused to rotate in the tube by the pin 12, which also traverses the recess 19 in said cylinder, serves to close the offset portions of the bayonet slot and said cylinder is frictionally held against rotation by the pressure exerted by the coil spring 23. It is of course, understood that the friction provided by the coil spring 23 is not great enough to interfere with the turning of the handle by hand.

It is believed that the many advantages of a suction head and handle constructed in accordance with this invention will be readily understood and although the preferred em-

bodiment of the invention is as illustrated and described, it is to be understood that changes in the details of construction may be had which will fall within the scope of the invention as claimed.

70

What is claimed is:

1. A device of the character described comprising a socket member for attachment to a suction box head, spaced flanges on the socket member, oppositely disposed brackets mounted on the suction head having inturned forked end portions slidably engaging the sides of the socket member, intermediate the flanges, and a coupling pin extending transversely through the socket member.

75

2. A device of the character described for use in connection with suction box heads comprising a tubular socket member having an internally threaded portion on one end, said socket member being adapted for threaded connection with the suction box head, said socket member being further provided with a longitudinal bore of uniform diameter, and a threaded counter-bore merged with the first named bore, a pair of longitudinally spaced flanges formed on the socket member, a pair of oppositely disposed brackets having inwardly turned bifurcated end portions slidably engaging the sides of the socket member intermediate the flanges, a transverse handle coupling pin extending through the uniform bore, and an outwardly turned guide flange on the lower end of the socket member.

80

3. A device of the character described, for use in connection with the suction box head of paper making machines, of a threaded neck mounted on the head, an internally threaded socket member threaded on the neck, said socket member being provided with an unthreaded uniform bore, longitudinally spaced annular flanges on the outer periphery of the socket member, a pair of oppositely disposed brackets mounted on the head on opposite sides of the neck and having inturned forked end portions engaging the sides of the socket member intermediate the flanges, a transverse coupling pin extending through the unthreaded bore, and an outwardly directed guide flange on the lower end of the socket member.

85

4. A device of the character described for use in connection with the suction box heads of paper making machines of a socket mounted on said head and having a longitudinal bore and a transverse coupling pin extending therethrough, and a detachable handle in said socket and comprising an elongated hollow tube having bayonet slots in one end, a cylindrical reinforcing block having a bifurcated end mounted in the end portion of the tube, said cylindrical block constituting a reinforcement for the end of the tube, and means for rotatably maintaining said blocks in said tube.

90

5. A device of the character described for

95

mounting on the suction box heads of paper making machines comprising a socket member having a longitudinal bore therethrough, and a transverse coupling pin extending through the bore, a detachable handle for connection in the bore, said handle comprising an elongated tube having bayonet slots in one end, a cylindrical reinforcing block having an open ended slot therein, mounted in the 10 end of the tube, means for rotatably retaining the reinforcing block in the tube and resilient means for frictionally preventing rotation of the reinforcing block in the tube.

6. A device of the character described for 15 connection with the suction box head of paper making machinery comprising a socket member having a longitudinal bore and a transverse coupling pin extending through the bore, said socket member mounted on the suction box head, and a detachable handle for connection with the socket member in the bore thereof and comprising an elongated hollow tube, said tube being provided, at one end, with oppositely disposed bayonet slots, said 20 slots for the reception of the cross pin in the bore when the tube is inserted therein, a bifurcated cylindrical reinforcing block mounted on the end of the tube, the furcations thereon adapted to extend on opposite sides 25 of the cross pin in the socket member, said reinforcing block being provided adjacent its lower end with an annular groove, a retaining element mounted in the tube and protruding into the tube for rotatably retaining the reinforcing block in said tube, a stop member mounted in the tube in spaced relation to the reinforcing block, and an expandable spring having its opposite ends engaged 30 with the stop member and the opposed end of the reinforcing block for causing the latter to be frictionally held against rotation in 35 the tube.

In testimony whereof we affix our signatures.

45 JOHN REAGAN.
ARTHUR BERNARD.
